UNITED STATES PATENT OFFICE

OLAI BORGEN, OF RENNER, SOUTH DAKOTA

ELEVATING DEVICE

Application filed August 15, 1929. Serial No. 386,071.

This invention appertains to garages for automobiles and has for one of its primary objects the provision of novel means for forming a garage in a basement or sub-cellars 5 of a residence or building below the normal ground level, with novel means for raising and lowering the vehicle into and out of the garage thus formed.

Another important object of my invention 10 is the provision of novel means for storing automobiles below the normal ground level adjacent to and communicating with the cellar of a building or residence, said means embodying a vertically movable platform for receiving the automobile, with novel means for raising and lowering the platform so that the vehicle can be lowered into or raised out of the garage without undue effort on the part 15 of the driver of the automobile, thereby rendering the garage adaptable for residences where the automobile is used daily.

A further object of my invention is the provision of a cover for the garage and novel means for facilitating the raising and lowering of the cover of the garage, whereby the same can be conveniently manipulated both 20 from the inside and outside of the garage without undue exertion on the part of the operator.

A still further object of my invention is to 25 provide novel means for raising and lowering the platform for the automobile by the automobile itself, thereby rendering it unnecessary to provide an external source of power.

A still further object of my invention is to 30 provide an improved device for raising and lowering automobiles into and out of underground garages of the above character, which will be durable and efficient in use, one that 35 will be simple and easy to manufacture, and one which can be placed upon the market and incorporated with a building at a small cost.

With these and other objects in view, the 40 invention consists in the novel construction, arrangement and formation of parts, as will be hereinafter more specifically described, claimed, and illustrated in the accompanying drawings, in which drawings:

50 Figure 1 is a top plan view of my improved

garage showing the cover thereof in its raised position, the wall of the adjacent residence or other building being shown in horizontal section;

Figure 2 is a vertical longitudinal section 55 through my improved garage taken on the line 2—2 of Figure 1 looking in the direction of the arrows showing the platform for the automobile in its lowered position and the cover for the garage in its lowered position;

Figure 3 is a similar view looking in the opposite direction from Figure 2 and taken on the line 3—3 of Figure 1 looking in the direction of the arrows;

Figure 4 is a transverse section taken on 60 the line 4—4 of Figure 1 looking in the direction of the arrows;

Figure 5 is a similar view looking in the opposite direction and taken on the line 5—5 of Figure 1 looking in the direction of the 70 arrows;

Figure 6 is a fragmentary longitudinal section through the counterbalancing weight employed for the platform for the automobile;

Figure 7 is a fragmentary top plan view 75 of the weight, and

Figure 8 is a detail transverse section through the counterbalancing weight for the platform for the automobile taken on the 80 line 8—8 of Figure 6.

Referring to the drawings in detail, wherein similar reference characters designate corresponding parts throughout the several views, the letter A generally indicates my improved underground garage and B a residence or other building beside which the garage can be built.

In building my improved garage I excavate a pit 10 alongside of the building B of 90 the desired dimensions to accommodate an automobile and the walls of the pit are preferably reinforced by concrete or the like. The pit is preferably dug at a point convenient to the residence B so that access can be had thereto from the cellar of the residence whereby persons can enter into and leave the garage from the cellar of the house. The communication between the cellar and the garage permitting the keeping of the 95 100

garage warm from the cellar in the winter season.

The ceiling or roof of the garage is provided with a suitable opening 13 preferably of slightly larger dimensions than an automobile and this opening can be closed by a suitable door 14. This door is preferably constructed of relatively light material such as wooden frame members covered with sheet metal and the same is provided at one longitudinal edge with pintles 15 rotatably mounted in bearing brackets 16 anchored in the ground at one side of the door.

In order to facilitate the raising and lowering of the door or cover 14, I provide counterbalancing weights 17 and 18 therefor. The weight 17 is formed relatively heavy and is connected to the lower end of a cable 19 having its intermediate portion trained over a guide pulley 20 secured to the side wall of the building B above the ground level. The end of the cable opposite to the weight 17 is secured to the trap door 14. The weight 18 is of a smaller size and is held in a plane higher than the heavy weight 17 and is secured to the lower end of a relatively long cable 21 which is trained about suitable guide pulleys 22 secured to one wall of the garage or pit 10 adjacent to the opposite ends thereof. The pulleys 22 are arranged adjacent to the opposite end of the door opening 13 and the cable 21 is extended through the wall or ceiling of the garage and is trained over a pulley 23 secured to the side wall of the building B. This cable is in turn attached to the trap door 14. The weights 17 and 18 are of such a size or weight as to effectively counterbalance the door 14 and when it is desired to raise the same, it is merely necessary to lift up on the door 14 and the weights will tend to move the door to its raised position. It can be seen that the heavy weight 17 will strike the floor of the garage first, but that the smaller weight will continue its pull on the door.

When it is desired to open the door from the inside of the garage, it is merely necessary to pull down on either one of the cables 19 or 21.

Arranged within the pit or garage 10 is a vertical movable platform 25 on which the vehicle is driven to permit the same to be raised and lowered into the pit or garage.

While the platform 25 may be constructed in any desired or preferred way, I have shown the same consisting of end transverse timbers 26 and longitudinally extending timbers 27. The longitudinal timbers 27 support U-shaped or L-shaped guide tracks or rails 28 on which the wheels of the vehicle are driven. As shown in Figure 2 of the drawings, the longitudinal timbers can be further braced by angle bars 29. This forms a strong and durable structure and this platform is of such a size as to completely fill the opening 13 in the

top of the pit or garage so that the automobile can be driven directly from the driveway onto the rails or tracks 28.

I have provided novel means for raising and lowering the platform into and out of the garage and I propose to use the power directly from the automobile for this purpose.

The platform and the weight of the car to be raised and lowered are nicely balanced by the use of a counterbalancing weight 35 which extends longitudinally of the pit or garage at one side of the platform.

This counterbalancing weight 35 is of novel construction and includes a base weight member 36 preferably formed of concrete having an I-beam 37 embedded therein. The I-beam has connected to the opposite ends thereof upstanding hanging loops 38 so as to permit the weight to be connected to the raising and lowering cables, as will be later described. The weight besides the base member 36 also includes any preferred number of concrete slabs 39 which are laid one upon the other on the base member over the loops 38, the concrete slabs being provided with openings 40 for this purpose. As heretofore stated, the platform and the weight of the car are nicely balanced by the counterbalancing weight 35 and thus more or less of the concrete slabs 39 are utilized, according to the weight of the car being raised or lowered.

Connected to the supporting loops or shackles 38 at each end of the platform are counterbalancing cables 41 and 42. These cables are first trained over supporting pulleys 43 and 44 and the cables 41 are then trained over second pulleys 45 and then downward and rigidly secured to the adjacent corners of the platform. The cables 42 are trained over pulleys 46 and are then brought down and rigidly secured to the other or inner corners of the platform. By this arrangement it can be seen that the platform is supported at all four corners.

A drum 47 is rotatably mounted in suitable bearings 50 carried by a suitable bracket structure 51 connected with the platform. Trained around the drum are hoisting and lowering cables 48 and 49 which are independent of the counterbalancing cables. The raising and lowering cables 48 and 49 have their lower ends attached to the drum 47 and the opposite ends of the cables lead to opposite diagonal corners of the platform and are trained over guide pulleys 49' carried thereby. These raising and lowering cables are then extended upwardly and rigidly secured to the opposite end walls of the pit adjacent to the top thereof. On one side of the drum I arrange a transversely extending drive shaft 52 which is journaled in the longitudinal beams 27 which can be provided with any preferred type of bearings therefor. The shaft 52 is provided with a worm 53 which meshes with a worm wheel 54 on the top of

the drum 47, whereby upon rotation of the worm 53, the drum will be rotated.

Keyed or otherwise secured to the shaft 52 adjacent to the opposite terminals thereof are drive pulleys or traction wheels 55 which extend through slots 56 in the guide tracks or rails 28 of the platform which receive the automobile. I also prefer to arrange in front of the drive pulleys or traction wheels 55 5 guide pulley wheels 57 which can be journalled in any preferred manner to the longitudinal beams 27 and these wheels 57 also extend through the slots 56 formed in said rails or tracks 28. It is to be noted that the wheels 15 55 and 57 are so placed as to permit the rear wheels of an automobile to be received therebetween.

From the foregoing it is obvious that when an automobile is driven on the tracks 28 with 20 the rear wheels resting between the pulley wheels 55 and 57 and that when the vehicle is driven in one direction, the drum 47 will be rotated thereby in one direction, and consequently wind up or pay off the cables 41 25 and 42 in opposite directions on the drum. When the rear wheels of the motor vehicle are driven in the opposite direction, the drum will consequently be rotated in the opposite direction and then the cables will be wound on or 30 paid off of the drum, as the case might be.

It is obvious that the winding up or the paying off of the cables 48 and 49 will effectively raise and lower the platform with the automobile thereon. In this process of raising 35 and lowering the platform by the power of the automobile, the counterbalancing weight 35 herein described will very materially help and it will in effect reduce the weight of the platform carrying the automobile.

40 In use of my improved device, the cover 14 for the pit or garage is moved to its raised position and considering that the platform 25 is already raised, the automobile is driven directly on the tracks 28. If preferred, after 45 the automobile is disposed on the tracks in such a manner that the rear wheels thereof will engage the pulley wheels 55 and 57 of the platform, the vehicle can be chained to the platform so as to prevent accidental forward 50 or rearward movement thereof incident to the turning of the rear wheels. The rear wheels can now be turned backwards or forwards as the case might be, in order to wind the drum in the desired direction and the counterbal- 55 ancing weight 35 will be raised and the platform and the vehicle will be lowered into the garage or pit.

The driver of the vehicle can now stop the engine and step out of the automobile and by 60 lifting up on the weights 17 and 18, the door 14 can be moved to its closed position. The vehicle will now be safely stored away and the driver thereof can enter the cellar of his house through the communicating doorway. 65 When it is desired to use the automobile

again, the operator pulls down on the weights 17 and 18 so as to raise the door 14 and the engine of the vehicle is started in the usual way. The gears are shifted so as to drive the rear wheels of the vehicle in the desired direction and the drum will be rotated so as to permit the lowering of the weight and the raising of the platform. After the platform has been raised to the desired level, the driver of the vehicle can then drive his car off of the platform into the driveway, after which the cover 14 is again moved to its lowered position. 70 75

As clearly shown in Figure 4, the platform 25 is slidably mounted by means of brackets 60 on supporting posts 61, which effectively guides the platform during its raising and lowering movement. 80

Changes in details may be made without departing from the spirit or the scope of this 85 invention, but:

What I claim as new is:

1. In an underground garage for automobiles, a vertically movable platform, said garage comprising side walls, a top wall having an entrance and exit opening therein, and a floor, said platform provided with transversely extending supporting members located at the ends thereof and adapted to rest upon the floor for supporting said platform above the floor when the platform is in its lowered position, means for raising and lowering the platform including a drum located below the platform and supported out of contact with the floor through the medium of said transverse members of said platform, cables wound on said drum in opposite directions, said cables being secured to the opposite walls of the garage adjacent the top thereof, guiding rods interposed between said top wall and said floor, means for anchoring said platform upon said guiding rods whereby said platform will be held against lateral and longitudinal shifting movement and at the same time will be permitted to have a raising and lowering movement, and traction wheels carried by said platform for driving said drum for winding and unwinding said cables upon the drum. 90 95 100 105 110

2. In an underground garage of the class described having side, end and top walls, said garage also having a floor, a movable platform, means adapted to contact with the floor for supporting the platform in spaced relation with respect to the floor when the platform is in its lowered position, vertically extending guide rods interposed between the floor and the top of the garage, means carried by the platform and engaging said rods for permitting raising and lowering of the platform and holding the platform against lateral and longitudinal shifting movement, lifting cables, an operating drum for winding said cables, pulleys for guiding said cables upon said platform and also upon the walls 115 120 125 130

of said garage, said cables being secured to the walls of the garage near the top thereof, counterbalancing means for facilitating the raising and lowering of the platform, the top of the garage being provided with an opening for permitting an automobile carried by the platform to be raised out of the garage and lowered into the same, and a cover for the opening formed in the top of the garage.

10 In testimony whereof I affix my signature.
OLAI BORGREN.
